(57) **CLAIM**

The ornamental design for a multi-device wireless charging station, as shown and described.

DESCRIPTION

FIG. 1 is a top perspective view of a multi-device wireless charging station showing Applicant's new design.

FIG. 2 is a bottom perspective view of the multi-device wireless charging station of FIG. 1;

FIG. 3 is a left-side elevation view of the multi-device wireless charging station of FIG. 1;

FIG. 4 is a right-side elevation view of the multi-device wireless charging station of FIG. 1;

FIG. 5 is a rear elevation view of the multi-device wireless charging station of FIG. 1;

FIG. 6 is a front elevation view of the multi-device wireless charging station of FIG. 1;

FIG. 7 is a top plan view of the multi-device wireless charging station of FIG. 1; and,

FIG. 8 is a bottom plan view of the multi-device wireless charging station of FIG. 1.

(Continued)

The broken lines in the drawings illustrate portions of the multi-device wireless charging station that form no part of the claimed design.
